UNITED STATES PATENT OFFICE.

CONRAD A. WELLING, OF ST. LOUIS, MISSOURI.

INTERNAL-COMBUSTION-ENGINE GOVERNOR.

1,411,650.

Specification of Letters Patent. Patented Apr. 4, 1922.

Application filed June 10, 1918. Serial No. 239,340.

To all whom it may concern:

Be it known that I, CONRAD A. WELLING, a citizen of the United States of America, and a resident of the city of St. Louis and State of Missouri, have invented certain new and useful Improvements in an Internal-Combustion-Engine Governor, of which the following is a specification.

The primary object of this invention is to provide an improved cut-off mechanism relative to internal combustion motors for reducing the gas supply from the carburetor to the firing cylinders of the motor after the motor has attained a given mileage speed.

Another object is to provide an improved cut-off member that will operate instantaneously when a given high speed is attained, so that the full volume of gas supply being fed to an internal combustion engine will be so quickly reduced that the high speed of an internal combustion motor will be immediately limited in accordance with the reduced amount of gas supply given.

A further object of this invention is to provide an improved cut-off mechanism relative to the gas supply of an internal combustion motor, which while reducing the volume of gaseous fuel will not reduce the fuel enough to stop the motor.

A still further object is to provide an improved arrangement of parts relative to operating this improved gas cut-off member.

Other and further objects will appear in the specification and be specifically pointed out in the appended claims, reference being had to the accompanying drawings exemplifying the invention, and in which,

Figure 1 is a side elevation, partly in section, showing this improved gas cut-off member located in the gas manifold inlet pipe which leads from the carburetor to the inlet manifold of an internal combustion motor, and the operating parts relating to said cut-off member.

Figure 2 is a front end elevation, partly in section, showing the gearing and operating parts relative to this improved gas cut-off member.

Figure 3 is a fragmentary vertical section taken approximately on the line III—III of Fig. 2.

Figure 4 is a cross section taken on the line IV—IV of Fig. 1, showing the gas cut-

off member in a closed position relative to the manifold inlet pipe.

Referring to the drawings 1 designates a portion of an internal combustion motor, 2 the cam shaft gear which meshes with the crank shaft pinion, not shown, said gear, 60 crank shaft and pinion being ordinary relative to internal combustion motors, said gear 2 being mounted on the cam shaft 5, and is enclosed in the housing 6.

Mounted on the cam shaft 5 outside of the 65 spur gear housing 6 is a pinion 7, said pinion meshing with an idler gear 8, which is mounted on the stub shaft 9, and meshing with said gearing 8 is a pinion 10 which has the same ratio as the pinion 7, said pinion 10 being mounted on the timer shaft 11.

Mounted over said gearings 7, 8 and 10 is a suitable housing 12 to which is secured a front plate 13. Mounted on the extending end of the shaft 11 outside of the front plate 75 13 is a contact maker 36, which is co-operable with the timer 37 mounted thereover.

The shaft 11 parallels the crank case, not shown, and slidably mounted on said shaft at the end opposite to the gearing 10 is a 80 sleeve 14, said sleeve being slidably secured to the shaft by the key 15. Formed on one end of said sleeve 14 is a collar 16, having an annular groove 17, and formed on the opposite end of said sleeve is a shoulder 18, 85 to which are secured a pair of oppositely disposed expanding arms 19 of a governor 20, each of said arms carrying a weight 20 intermediate of their ends, the opposite ends of said arms being secured to a collar 21, 90 which is rigidly secured to the shaft 11.

Slidably supported in a pair of end guides 22 is a cross head 23, and extending from said cross head, intermediate of its ends, is a bifurcated member 24, the lower end of said 95 bifurcated member straddling the reduced portion 25 of the collar 16.

Pivots secured to the cross head 23 at 26 is one end of an upwardly extending lever 27, said lever being slidably and swingingly supported in a guiding member 28. The upper end of the lever 27 is split as designated at 29, and mounted in said split portion and secured thereto is one end of an upwardly extending leaf spring 30, said lever 27 and leaf spring 100 30 forming a toggle lever, the upper end of said spring 30 having a bearing portion 31 which is pivotally secured to one end of a

2
rocker arm 32 which is rigidly mounted to a shaft 33, said shaft being mounted in opposing sides of the gas manifold inlet pipe 34, and carried by said shaft 33 in said pipe 34 is a butterfly valve 35.

6 As afore related in the objects of this invention, this improved cut-off mechanism is designed so as to prevent a vehicle from attaining a higher speed of travel than the 10 proper mileage per hour allowed by law, as it is well known how hired operators of automobiles quite often drive the automobile, which is in their care, to the limit.

15 In the operation of this improved device, when a vehicle equipped with the same is run at a normal speed, the butterfly valve 35, which is located in the manifold inlet pipe is in a position shown in dotted lines A, in Fig. 1, so that the gas can pass by 20 said valve to the gas manifold 38, but when the motor begins to attain a higher speed, the timer shaft 11 on which the governor 20 is mounted will cause the weights 20* to be carried outwardly, thereby exerting a pull 25 on the sleeve 14, and drawing the cross head 23 in the direction of travel of the sleeve 14, and inasmuch as the lever 27 is pivoted at 26 to said cross head, the lower end of said lever will be pulled therewith, while the 30 upper end of said lever will be swung rearwardly and pulled slightly down through the guiding member 28.

35 Attention is called to the leaf spring 30 which is so long in length relative to its connections between the upper end of the lever 27 and the lower end of the rocker arm 32, that a bend is forced in said spring. Therefore, as the lever 27 is slightly drawn downwardly during the travel of the cross head 40 23 as just described, said spring 30 will be somewhat straightened, and at the same time a force will be given to said spring from the lever 27 in a direction towards which the upper end of said lever is moving, and as 45 soon as the leaf spring 30 is straightened, the force applied thereto from said lever 27 will force the upper end of said leaf spring over center, the movement of said leaf spring being instantaneous and positive as regards 50 its throwing movement. This action of the lever 27 on the leaf spring 30 will instantly throw the butterfly valve 35 to a closed position, as shown by dotted lines B, Fig. 1, thereby cutting off the full force of gaseous fluid that was heretofore being fed to the motor, in which instance the motor cannot attain a higher speed.

55 In order to prevent a complete shutting off of the gas supply, the butterfly valve 35 is perforated with a plurality of openings 39. As soon as the speed of the motor has been checked as just related, it is obvious that if the speed of the motor lowers, the governor weights 20* will be moved inwardly by the arms 19 thereof, thereby mov-

ing the sleeve 14 back to its normal position, and instantly returning the lever 27 to its position, and the leaf spring 30 therewith, and throwing the valve 35 to its normal position, in which case the full force of fuel 70 can be again fed to the motor.

75 After the valve 35 has been operated to a closed position relative to the speed of the motor, the perforations 39 formed in said valve will allow enough fuel to pass therethrough so that the motor can maintain the speed attained when the valve was operated to a closed position, but it is self evident that a higher speed of the motor cannot be attained relative to a pulling load after the 80 valve has been moved to its cut-off position.

85 In a device of this character, it has been found that it is essential to quickly open and close the valve 35, and not operate the same slowly towards or away from a closed position, as it is often necessary in hill climbing to give the motor a full volume of fuel, and if a slow operating device were used in connection with the motor speed, the fuel supply will become less as the device is operated 90 towards closing, whereas with this improved device, the cut-off mechanism will not operate towards closing, only when a maximum engine speed has been attained, in which instance an ample supply of fuel can be fed 95 unchecked to the motor relative to hill climbing efforts, and the like.

For the mounting of the butterfly valve 35 to the shaft 33, the shaft is split as designated at 40, in which case the valve is 100 mounted in the split of the shaft, and is held in place by the pins 41.

105 In order to provide for the proper mounting of the valve 35 to the shaft 33 as described, the inlet pipe 34 and gas manifold 38 are made in two parts, the valve and shaft being mounted in place before the pipe 34 is secured to the manifold 38, in which the shaft is first mounted through the opening 42 formed in the pipe 34, and the inner end 110 of said shaft engaged in the enclosed bearing 43 which is also formed in the pipe 34. The butterfly valve is then introduced into the pipe 34 from the upper end thereof and engaged in the split shaft 33, and then secured in place by the pins 41; the manifold 38 is then secured to the pipe 34. This manner of mounting the valve to the shaft 33 will prevent the shaft from being withdrawn from its bearings, thereby preventing 115 120 the valve from being tampered with.

125 What I claim is:

1. A cut-off mechanism for an internal combustion motor comprising a governor, a valve therefor, a resilient toggle lever co-operable with said valve having a slidably mounted pivot, and co-operable means whereby said governor is adapted to apply a sliding movement to the pivot of said lever. 130

2. A cut-off mechanism for an internal combustion motor, comprising a governor, a slidably mounted sleeve related to said governor, a pivoted resilient toggle lever co-operable with said sleeve adapted to have its pivoted end slidably moved by said sleeve, and a swingingly mounted valve to be actuated by said toggle lever. 25
5. A cut-off mechanism for an internal combustion motor, comprising a gas inlet pipe, a valve swingingly mounted in said pipe, a pivoted resilient toggle lever co-operable with the axis of said valve, and a governor for imparting movement to the pivoted end of said toggle lever. 30
10. A cut-off mechanism for an internal combustion motor, comprising a gas inlet pipe, a valve swingingly mounted in said pipe, a pivoted resilient toggle lever connected to said arm of said axis, a revolute shaft, and a governor mounted on said shaft for imparting movement to the pivoted end of said toggle lever. 35
15. A cut-off mechanism for an internal combustion motor, comprising a gas inlet pipe, a valve swingingly mounted in said pipe, a resilient toggle lever co-operable with the axis of said valve having a slideable swinging end, a revolute shaft, and a governor on said shaft for imparting movement to the slideable end of said toggle lever. 40
20. The combination of a gas inlet pipe, a valve swingingly mounted in said pipe, a pivoted resilient toggle lever co-operable at one end with said axis, a cross head for supporting the pivoted end of said lever, and a governor co-operable with said cross head. 45

CONRAD A. WELLING.
